MIXER DEVICE

TECHNICAL FIELD

The present invention relates to a mixer device.

BACKGROUND ART

Conventionally, a mixer device for mixing materials to be mixed is known.

For example, Japanese Utility Model Registration No. 3160227 discloses a mixer provided with a mixing tank, an axis body that penetrates the mixing tank, a mixing blade attached to the axis body via an arm in the mixing tank, and a driving motor that rotates the axis body.

However, the above mixer does not have a battery that supplies electric power to the driving motor. Accordingly, so as to operate the driving motor, it is required to supply the electric power from an external fixed power source to the driving motor via a cable. Accordingly, the range of movement of the mixer is limited within the reach of the cable, and thus the mobility of the mixer may decrease.

Further, in the above mixer, many heavy objects are arranged on an upper portion of the mixer. Accordingly, the center of gravity of the mixer becomes high, so that the stability of the mixer may decrease.

SUMMARY OF THE INVENTION

In view of the above background, an object of the present invention is to provide a mixer device with high mobility and stability.

To achieve such an object, one aspect of the present invention provides a mixer device (1), comprising: a drum (3) configured to store materials to be mixed; a device body (4) configured to rotatably support the drum; an electric motor (6) configured to apply a rotational driving force to the drum; and a battery (8) configured to supply electric power to the electric motor, wherein the battery is arranged below the drum.

According to this aspect, the mixer device comprises the battery configured to supply the electric power to the electric motor. Accordingly, it is not necessary to supply the electric power to the electric motor from an external fixed power source via a cable. Accordingly, the mixer device can be moved freely, and the mobility of the mixer device can be improved.

Further, the battery, which is a heavy object, is arranged below the drum. Accordingly, the center of gravity of the mixer device can be lowered, and the stability of the mixer device can be improved.

In the above aspect, preferably, the device body includes a pair of leg portions (24, 25) arranged on both sides of the drum in a horizontal direction, and the battery is attached to the device body and arranged between the pair of leg portions.

According to this aspect, the weight balance on the pair of leg portions is improved. Accordingly, the stability of the mixer device can be further improved.

In the above aspect, preferably, the device body further includes a coupling portion (26) extending horizontally and coupling the pair of leg portions, the coupling portion is arranged below the drum, and the battery is arranged below the coupling portion.

According to this aspect, the center of gravity of the mixer device can be further lowered. Accordingly, the stability of the mixer device can be further improved.

2

In the above aspect, preferably, the battery is attached to at least one of the leg portions and the coupling portion.

According to this aspect, the device body can stably support the battery. Accordingly, the stability of the mixer device can be further improved.

In the above aspect, preferably, the drum is configured to rotate around a rotation axis (X), and the battery overlaps with the rotation axis in a top view.

According to this aspect, when the drum swings according to the rotation of the drum, it is possible to suppress the large swing of the entire mixer device. Accordingly, the stability of the mixer device can be further improved.

In the above aspect, preferably, a wheel (29) is attached to a lower end of the device body, and a lower end of the battery is arranged higher than an axis (29A) of the wheel.

According to this aspect, by ensuring a sufficient gap between the battery and an installation surface of the mixer device, it is possible to prevent the battery from coming into contact with the installation surface. Accordingly, the mobility of the mixer device can be further improved.

In the above aspect, preferably, the lower end of the battery is arranged lower than an upper end of the wheel.

According to this aspect, the center of gravity of the mixer device can be lowered while ensuring a sufficient gap between the battery and the installation surface of the mixer device. Accordingly, the stability of the mixer device can be further improved.

In the above aspect, preferably, the battery includes: a battery pack (61); and a battery case (62) configured to detachably store the battery pack.

According to this aspect, when the mixer device is not in use, the mixer device can be moved in a state where the battery pack is detached from the battery case. Accordingly, the mobility of the mixer device can be further improved.

In the above aspect, preferably, the battery case has an opening (64) for attaching and detaching the battery pack, and the opening is covered with an openable cover (65).

According to this aspect, the cover can protect the battery pack. Accordingly, even if the materials to be mixed (for example, cement) or the mixed material (for example, concrete) drips from the drum above the battery, it is possible to prevent the dripping materials to be mixed or the dripping mixed material from contaminating the battery packs.

In the above aspect, preferably, the drum includes: a drum body (11) with a bottomed cylindrical shape; and an annular flange (12) protruding from an outer circumferential surface of the drum body, and the drum body is arranged within a horizontal width of the battery when viewed in a prescribed direction.

According to this aspect, the weight balance of the mixer device is improved. Accordingly, the stability of the mixer device can be further improved.

Thus, according to the above aspects, it is possible to provide a mixer device with high mobility and stability.

BRIEF DESCRIPTION OF THE DRAWING(S)

FIG. 1 is a front view showing a state where a drum is in a reference posture in a mixer device according to an embodiment of the present invention;

FIG. 2 is a plan view showing the state where the drum is in the reference posture in the mixer device according to the embodiment of the present invention;

FIG. 3 is a front view showing a state where the drum is in a tilt posture in the mixer device according to the embodiment of the present invention;

FIG. 4 is a front view showing a state where a handle is lifted in the mixer device according to the embodiment of the present invention; and

FIG. 5 is a front view showing a state where the drum is in a reference posture in a mixer device according to another embodiment of the present invention.

DETAILED DESCRIPTION OF THE INVENTION

Concrete Mixer 1

Hereinafter, a concrete mixer 1 (an example of a mixer device) according to the embodiment of the present invention will be described with reference to the drawings. The concrete mixer 1 is a device for mixing materials to be mixed such as cement, aggregate (sand and gravel), water, admixture, and the like to produce concrete.

With reference to FIGS. 1 and 2, the concrete mixer 1 includes a drum 3 configured to store the materials to be mixed, a device body 4 configured to rotatably support the drum 3, a handle 5 attached to the device body 4, an electric motor 6 configured to apply a rotational driving force to the drum 3, a transmission member 7 configured to transmit the rotational driving force of the electric motor 6 to the drum 3, and a battery 8 configured to supply electric power to the electric motor 6. Hereinafter, the components of the concrete mixer 1 will be described one by one.

Drum 3

The drum 3 of the concrete mixer 1 is a hollow member. The drum 3 is configured to rotate around a rotation axis X. Further, the drum 3 is configured to tilt around a tilt axis Y extending in the lateral direction (horizontal direction). That is, the axial direction of the tilt axis Y is the lateral direction. As the drum 3 tilts around the tilt axis Y, the posture of the drum 3 switches from a reference posture (see FIGS. 1 and 2) to a tilt posture (see FIG. 3). The reference posture is a posture in which the rotation axis X extends along the vertical direction. The tilt posture is a posture in which the rotation axis X tilts with respect to the vertical direction. Hereinafter, the components of the concrete mixer 1 will be described based on a state where the drum 3 is in the reference posture.

With reference to FIGS. 1 and 2, the drum 3 includes a drum body 11 with a bottomed cylindrical shape around the rotation axis X and an annular flange 12 protruding from an outer circumferential surface of the drum body 11. A plurality of stirring blades 14 are fixed inside the drum body 11. A circular feeding port 15 is opened at an upper end of the drum body 11, and the materials to be mixed are fed into the drum body 11 through the feeding port 15. A rack gear 16 is provided on a lower surface of the flange 12 over an entire circumference of the flange 12.

Device Body 4

The device body 4 of the concrete mixer 1 includes a support member 21 and a rotating member 22 rotatably supported by the support member 21.

The support member 21 includes a pair of leg portions 24, 25 (a first leg portion 24 and a second leg portion 25) arranged on both sides of the drum 3 in the lateral direction (horizontal direction) and a coupling portion 26 extending in the lateral direction (horizontal direction) and coupling the pair of leg portions 24, 25.

The first leg portion 24 of the support member 21 includes an upper frame 27 extending linearly in the up-and-down direction and a pair of lower frames 28 extending from a lower end of the upper frame 27 to a lower front side and a lower rear side. A pair of wheels 29 are rotatably attached to lower ends of the pair of lower frames 28. Each wheel 29 is rotatably provided around an axis 29A. The concrete mixer 1 does not have a drive source for rotating the wheel 29 (a drive source to cause the concrete mixer 1 to travel). That is, the concrete mixer 1 is not a device that travels by itself but a device that travels as being pushed by a hand.

The second leg portion 25 of the support member 21 extends linearly in the up-and-down direction. The wheel 29 is not attached to a lower end of the second leg portion 25. The lower end of the second leg portion 25 is in contact with the ground G (an example of an installation surface of the concrete mixer 1).

The coupling portion 26 of the support member 21 is arranged below the drum 3. A right end of the coupling portion 26 is fixed to a lower end of the upper frame 27 of the first leg portion 24. A left end of the coupling portion 26 is fixed to the center of the second leg portion 25 in the up-and-down direction.

The rotating member 22 includes a pair of engagement tubular portions 31, 32 (a first engagement tubular portion 31 and a second engagement tubular portion 32) arranged on both sides in the lateral direction of the drum 3, and a connecting portion 33 that connects the pair of engagement tubular portions 31, 32.

The pair of engagement tubular portions 31, 32 of the rotating member 22 has a cylindrical shape around the tilt axis Y. The first engagement tubular portion 31 is rotatably engaged with the upper frame 27 of the first leg portion 24 of the support member 21. The second engagement tubular portion 32 is rotatably engaged to an upper portion of the second leg portion 25 of the support member 21.

The connecting portion 33 of the rotating member 22 has a substantially U-shape protruding downward. A right end of the connecting portion 33 is fixed to the first engagement tubular portion 31. A left end of the connecting portion 33 is fixed to the second engagement tubular portion 32. A central portion of the connecting portion 33 in the lateral direction extends below the drum body 11 in the lateral direction. At the central portion of the connecting portion 33 in the lateral direction, a bearing 34 protruding upward is provided. The bearing 34 is engaged with a lower end of the drum body 11, and rotatably supports the drum 3.

Handle 5

The handle 5 of the concrete mixer 1 is arranged on an opposite side of the drum 3 with respect to the second leg portion 25 of the support member 21 of the device body 4. The handle 5 includes a first arm 41 extending in the up-and-down direction and a second arm 42 extending from an upper end of the first arm 41 to a left side (an outside in the lateral direction). A lower end of the first arm 41 is fixed to the second engagement tubular portion 32 of the rotating member 22 of the device body 4. A grip 43 is fixed to an outer circumference of the second arm 42.

Electric Motor 6

The electric motor 6 of the concrete mixer 1 is arranged on an opposite side of the handle 5 with respect to the drum 3. The electric motor 6 is arranged on an opposite side of the drum 3 with respect to the first leg portion 24 of the support

member 21 of the device body 4. The electric motor 6 is fixed to the upper frame 27 of the first leg portion 24. The electric motor 6 has a rotatable motor shaft (not shown). A power switch 45 is provided on a front surface of the electric motor 6.

Transmission Member 7

The transmission member 7 of the concrete mixer 1 includes a transmission shaft 51 extending in the lateral direction along the tilt axis Y and a pinion gear 52 fixed to a left end of the transmission shaft 51. The transmission shaft 51 penetrates the first engagement tubular portion 31 of the rotating member 22 of the device body 4, and is rotatably supported by the first engagement tubular portion 31. The transmission shaft 51 is connected to the motor shaft (not shown) of the electric motor 6. The transmission shaft 51 may be directly fixed to the motor shaft of the electric motor 6, or indirectly connected to the motor shaft of the electric motor 6 via a gear mechanism or the like. The pinion gear 52 meshes with the rack gear 16 provided on the lower surface of the flange 12 of the drum 3. Accordingly, the pinion gear 52 and the rack gear 16 compose a rack-and-pinion mechanism 53.

Battery 8

With reference to FIG. 1, the battery 8 of the concrete mixer 1 is arranged below the drum 3. The battery 8 is arranged between the pair of leg portions 24 and 25 of the support member 21 of the device body 4. The battery 8 is arranged below the coupling portion 26 of the support member 21.

A left end of the battery 8 is arranged more leftward than a left end of the drum body 11, and a right end of the battery 8 is arranged more rightward than a right end of the drum body 11. That is, in the present embodiment, the drum body 11 is arranged within the width W1 of the battery 8 in the lateral direction (horizontal direction) when viewed in the front-and-rear direction (the direction perpendicular to the lateral direction and the vertical direction). In another embodiment, the drum body 11 does not have to be arranged within the width W1 of the battery 8 in the lateral direction.

An upper end of the battery 8 is arranged lower than a lower end of the electric motor 6. A lower end of the battery 8 is arranged higher than the axis 29A of each wheel 29. The lower end of the battery 8 is arranged lower than an upper end of the wheel 29.

With reference to FIG. 2, the battery 8 overlaps with the rotation axis X of the drum 3 in a top view. The battery 8 overlaps with the feeding port 15 of the drum body 11 of the drum 3 in a top view. The center of the battery 8 in the front-and-rear direction matches the tilt axis Y.

With reference to FIGS. 1 and 2, the battery 8 includes a plurality of battery packs 61 and a battery case 62 configured to detachably store the plurality of battery packs 61. The plurality of battery packs 61 and the battery case 62 overlap with the drum body 11 of the drum 3 in a top view.

For example, each battery pack 61 consists of a secondary battery such as a lithium-ion battery. The battery pack 61 is connected to the electric motor 6 via a cable 63 and configured to supply the electric power to the electric motor 6.

The battery case 62 is fixed to the second leg portion 25 and the coupling portion 26 of the support member 21 of the device body 4. In another embodiment, the battery case 62 may be fixed to the first leg portion 24 and the coupling

portion 26 of the support member 21 or fixed to both leg portions 24, 25 and the coupling portion 26 of the support member 21.

An opening 64 for attaching and detaching the battery packs 61 is provided on a front surface of the battery case 62. In another embodiment, the opening 64 may be provided on a surface (for example, an upper surface) other than the front surface of the battery case 62. The opening 64 is covered with an openable cover 65.

Operation of the Concrete Mixer 1

When using the concrete mixer 1, the user switches on the power switch 45 of the electric motor 6 in a state where the drum 3 is in the tilt posture. Accordingly, the electric motor 6 operates, and thus the motor shaft (not shown) of the electric motor 6 rotates. The rotation of the motor shaft of the electric motor 6 is transmitted to the transmission member 7, and thus the transmission member 7 rotates. The rotation of the transmission member 7 is transmitted to the flange 12 of the drum 3 via the rack-and-pinion mechanism 53, and thus the drum 3 rotates around the rotation axis X. Accordingly, the materials to be mixed stored in the drum 3 are mixed, and thus concrete is generated.

Tilt of the Drum 3

When the user operates the handle 5 forward in a state where the drum 3 is in the reference posture (see FIGS. 1 and 2), the handle 5, the rotating member 22 of the device body 4, and the drum 3 rotate integrally in one direction around the tilt axis Y. Accordingly, the posture of the drum 3 is switched from the reference posture to the tilt posture (see FIG. 3). That is, the drum 3 tilts.

On the other hand, when the user operates the handle 5 rearward in a state where the drum 3 is in the tilt posture, the handle 5, the rotating member 22 of the device body 4, and the drum 3 rotate around the tilt axis Y in the direction opposite to the above one direction. Accordingly, the posture of the drum 3 is switched from the tilt posture to the reference posture. That is, the tilt of the drum 3 is canceled.

Movement of the Concrete Mixer 1

With reference to FIG. 4, when moving the concrete mixer 1, the user lifts the handle 5 to separate the lower end of the second leg portion 25 of the device body 4 from the ground G. Accordingly, only each wheel 29 is in contact with the ground G. In this state, when the user pushes any portion of the concrete mixer 1 in the lateral direction, the wheel 29 rotates and the concrete mixer 1 moves.

Effects

The concrete mixer 1 according to the present embodiment includes the battery 8 configured to supply the electric power to the electric motor 6. Accordingly, it is not necessary to supply the electric power to the electric motor 6 from an external fixed power source via a cable. Accordingly, the concrete mixer 1 can be moved freely, and the mobility of the concrete mixer 1 can be enhanced.

Further, the battery 8, which is a heavy object, is arranged below the drum 3. Accordingly, the center of gravity of the concrete mixer 1 can be lowered. Accordingly, even when the concrete mixer 1 of a relatively large size is used, the stability of the concrete mixer 1 can be improved.

Further, each battery pack 61 is detachably housed in the battery case 62. Accordingly, when the concrete mixer 1 is not in use, the concrete mixer 1 can be moved in a state where the battery pack 61 is detached from the battery case 62. Accordingly, the mobility of the concrete mixer 1 can be improved. Further, when the concrete mixer 1 is not used, the battery pack 61 can be detached from the battery case 62 and used for a process other than a concrete forming process. Accordingly, the convenience of the battery pack 61 can be enhanced.

MODIFIED EMBODIMENT

In the above embodiment, the battery 8 includes a plurality of battery packs 61. In another embodiment, the battery 8 may include only one battery pack 61 as shown in FIG. 5.

In the above embodiment, the drum body 11 is arranged within the width W1 of the battery 8 in the lateral direction when viewed in the front-and-rear direction. In another embodiment, as shown in FIG. 5, the battery 8 may be arranged within the width W2 of the drum body 11 in the lateral direction when viewed in the front-and-rear direction.

In the above embodiment, the battery 8 is arranged below the coupling portion 26 of the support member 21 of the device body 4. In another embodiment, the battery 8 may be arranged above the coupling portion 26 as shown in FIG. 5. In this case, the battery 8 may be placed on the coupling portion 26.

In the above embodiment, the electric motor 6 rotates the drum 3 via the rack-and-pinion mechanism 53. In another embodiment, the electric motor 6 may be directly connected to a lower end of the drum 3 and rotate the drum 3 directly.

In the above embodiment, the wheels 29 are attached only to the first leg portion 24. In another embodiment, the wheels 29 may be attached to both the leg portions 24, 25, or may not be attached to either of the leg portions 24, 25.

In the above embodiment, the mixer device according to the present invention is applied to the concrete mixer 1. In another embodiment, the mixer device according to the present invention may be applied to a mixer device other than the concrete mixer 1 (for example, a mixer device that mixes gardening fertilizer or livestock feed). In other words, the mixed material generated by the mixer device according to the present invention does not have to be concrete.

Concrete embodiments of the present invention have been described in the foregoing, but the present invention should not be limited by the foregoing embodiments and various modifications and alterations are possible within the scope of the present invention.

The invention claimed is:

1. A mixer device, comprising:
a drum configured to store materials to be mixed;
a device body configured to rotatably support the drum;

an electric motor configured to apply a rotational driving force to the drum; and
a battery configured to supply electric power to the electric motor,
wherein the battery is arranged below the drum,
wherein the device body includes a pair of leg portions arranged on both sides of the drum in a horizontal direction, and
the battery is attached to the device body and arranged between the pair of leg portions.

5 2. The mixer device according to claim 1, wherein the device body further includes a coupling portion extending horizontally and coupling the pair of leg portions,
the coupling portion is arranged below the drum, and
the battery is arranged below the coupling portion.

15 3. The mixer device according to claim 2, wherein the battery is attached to at least one of the leg portions and the coupling portion.

20 4. The mixer device according to claim 1, wherein the drum is configured to rotate around a rotation axis, and
the battery overlaps with the rotation axis in a top view.

25 5. The mixer device according to claim 1, wherein a wheel is attached to a lower end of the device body, and
a lower end of the battery is arranged higher than an axis of the wheel.

6. The mixer device according to claim 5, wherein the lower end of the battery is arranged lower than an upper end of the wheel.

30 7. The mixer device according to claim 1, wherein the battery includes:
a battery pack; and
a battery case configured to detachably store the battery pack.

35 8. The mixer device according to claim 7, wherein the battery case has an opening for attaching and detaching the battery pack, and
the opening is covered with an openable cover.

9. A mixer device, comprising:
a drum configured to store materials to be mixed;
a device body configured to rotatably support the drum;
an electric motor configured to apply a rotational driving force to the drum; and
40 a battery configured to supply electric power to the electric motor,

45 wherein the battery is arranged below the drum,
wherein the drum includes:
a drum body with a bottomed cylindrical shape; and
an annular flange protruding from an outer circumferential surface of the drum body, and

50 a whole of the drum body is arranged within a horizontal width of the battery when viewed in a prescribed direction.
